UNITED STATES PATENT OFFICE.

GEORGE H. BECK, OF PHILADELPHIA, PENNSYLVANIA.

DESIGN FOR A SCREW-PROPELLER.

SPECIFICATION forming part of Design No. 27,432, dated July 27, 1897.

Application filed February 11, 1897. Serial No. 623,008. Term of patent 14 years.

To all whom it may concern:

Be it known that I, GEORGE H. BECK, a citizen of the United States, residing at Philadelphia, in the county of Philadelphia and State of Pennsylvania, have invented and produced a new and original Design for Screw-Propellers; and I do declare the following to be a full, clear, and exact description of the same, reference being had to the accompanying drawings, forming a part thereof.

My design relates to the shape and configuration of a screw-propeller.

In the accompanying drawings, Figure 1 is a side view; Fig. 2, a view in elevation of end A; Fig. 3, a view in elevation of end B.

Similar figures of reference refer to similar parts throughout the views.

The leading features of my design consist of a propeller having a substantially circular hub with spirally-shaped blades oppositely disposed in relation to the hub, said hub being perforated by a circular passage or opening, and pockets being formed in each end of the hub communicating with the opening and

located under the roots of the blades at the ends of the hub.

Referring to the drawings, 1 is the hub; 2 and 3, the spiral-shaped blades; 4, the circular passage or opening through the hub; 5, pockets at one end under the roots of the blades at that end, and 6, pockets under the roots of the blades at the opposite end. The pockets are of the shape shown, and each opens into the circular passage 4.

The shape, configuration, and relative disposition of the several features enumerated are clearly illustrated in the drawings.

Having described my invention, what I claim as new, and desire to secure by Letters Patent, is—

The design for a screw-propeller as herein shown and described.

In testimony whereof I affix my signature in presence of two witnesses.

GEORGE H. BECK.
